UNITED STATES PATENT OFFICE.

PETER E. KROEHLER, OF NAPERVILLE, ILLINOIS.

TABLE-BED, &c.

1,158,240.

Specification of Letters Patent. Patented Oct. 26, 1915.

Application filed October 18, 1913. Serial No. 795,875.

To all whom it may concern:

Be it known that I, PETER E. KROEHLER, a citizen of the United States, residing at Naperville, in the county of Dupage and State of Illinois, have invented a new and useful Improvement in Table-Beds, &c., of which the following is a specification.

My invention relates particularly to convertible table-beds; and my primary object is to provide a structure of the character indicated which is durable, readily convertible, and which presents a pleasing appearance.

The invention is illustrated in the accompanying drawings, in which—

Figure 1 represents an end elevational view of a table-bed constructed in accordance with my invention, the structure being shown in open condition; Fig. 2, a similar view showing the structure partly folded; Fig. 3, a detail of a locking device for securing an auxiliary frame employed to a swinging bed-housing section employed; Fig. 4, a broken plan view taken as indicated at line 4 of Fig. 1; Fig. 5, a broken plan section taken as indicated at line 5 of Fig. 1; Fig. 6, an enlarged broken vertical section, the section being taken parallel to one end of the table; Fig. 7, a broken section taken as indicated at line 7 of Fig. 2; Fig. 8, a broken elevational view, partly in section, showing the bed structure partly folded; Fig. 9, a broken sectional view taken as indicated at line 9 of Fig. 1; Fig. 10, a view similar to Fig. 9, but showing the parts folded; Fig. 11, a broken sectional view showing the position of certain parts after the folding operation has been carried farther than illustrated in Fig. 8 to complete the folding, these parts being shown inverted for ease of illustration, however; Fig. 12, a vertical sectional view parallel to one end of the table and showing the structure in table form; Fig. 13, a broken sectional view taken as indicated at line 13 of Fig. 12, but showing the table-top in the open position; and Fig. 14, an enlarged broken section taken as indicated at line 14 of Fig. 13.

In the embodiment shown, the invention comprises a table-frame A equipped with a movable top A¹, which is capable of being swung to the standing position shown in Fig. 1; a stationary bed-housing section B extending parallel with the rear side of the

table and constituting a panel; a swinging bed-housing section B¹ connected by pivots 1 with the end-portions of the table-frame near the base-portions of the end-standards; an auxiliary bed-supporting frame B² linked to the part B¹ and foldably related thereto; and a folding-bed C mounted on the members B¹ and B².

The table-frame may be of any approved construction. As shown, it comprises end-standards 2 which are rigidly connected at their rear upper portions by a rail 3. The end-standards are also rigidly connected in front of the piece 3 by the stationary housing-section B, which constitutes a rear panel for the table. The rear upper rail 3 is equipped with hinges whose short leaves 4 are rigidly secured to the rail 3, while the long leaves 4^a of the hinges are equipped with rollers 5 which engage channeled guides 6 that are rigidly secured to the rear portion of the lower surface of the table-top. This permits the table-top to swing to a standing position and to slide with relation to the hinges, so that the top will assume the standing position (inclining rearwardly slightly) shown in Figs. 1 and 13. The table-top is equipped with a front rail 7 and blocks 8. The blocks 8 are adapted to embrace the upper portion of the housing-section B¹ when it is in the standing position shown in Fig. 12. The blocks 8 are beveled as indicated at 8^a, to enable the table-top to slide over the member B¹ in the operation of opening the table-top.

The housing-section B¹ is preferably in the form of a box whose bottom 9 serves as a front panel for the table. The end-portions of the box are connected near their rear or lower extremities, through the medium of the pivots 1, with the lower portions of the end-standards of the table. The pivots 1 may comprise bolts which securely connect the box B¹ to the end-standards of the table-frame. Normally, the box-form member B¹ is disposed in a vertical plane, as shown in Fig. 12. It is equipped at its upper portion with short legs 10 adapted to rest upon the floor when the member B¹ is swung to the horizontal position shown in Fig. 6.

The auxiliary bed-supporting frame B² is a rectangular frame which, in the open condition, has its rear part supported by links 11 depending from brackets carried by the

member B¹. The front rail 12 of the member B² is equipped with clips 13 with which are connected, by pivots 14, legs 15 which swing in a plane parallel with the rail 12, the legs being equipped with studs 16 which move in sector-shaped slots 17 with which the clips 13 are provided. Legs 15 have their upper ends provided with extensions which are connected (Fig. 6) by links 18 with the front ends of levers 19 whose rear ends are connected, by pivots 20, with fittings 21 which are secured to the end-members of the frame B². The levers 19 are provided at their intermediate portions with slots 22 engaged by cam-studs 23 carried by links 24 whose lower ends are connected by pivots 25 to the ears which depend from the fittings 21. The upper ends of the links 24 are pivotally connected with a section of the folding-bed.

The folding-bed C comprises a main head-section 26; a main intermediate section 27; a main foot-section 28; a spacing section 29 which connects the sections 26 and 27; and a spacing section 30 which connects the sections 27 and 28. The section 26 is of U-form and has the intermediate portions of its arms mounted on elbow-levers 31 which are joined by pivots 32 to depending ears carried by the brackets 33 which are secured to the front corners of the box B¹. The spacing section 29 is supported by pivots 29^a on standards, or hangers, 34, secured to the rear portion of the frame B² and suitably trussed or braced with relation thereto. The rear ends of the bars constituting the section 29 are connected by pivots 35 with the front ends of the arms of the section 26. The levers 31 are connected at their elbow-portions by links 36 to the brackets 34. The main intermediate section 27 is connected by pivots 37 with the spacing section 29, and by pivots 38 with the spacing section 30.

The section 28 comprises a U-shaped member, the arms of which are connected by pivots 39 to the spacing-section 30. The section 28 is equipped with pivotally connected legs 40 having upward extensions connected by links 41 to the spacing-section 30. The legs 40 are connected by a brace, or rod, 42, and are equipped with arms 43 provided with locking notches 44 adapted to engage locking studs 45 with which the main intermediate section 27 is provided. The joints between the main sections and the spacing sections are such as to afford shoulders adapted to maintain the sections at right-angles to each other in the folded relation, and to maintain the sections against buckling when the bed-structure is in the extended condition.

The auxiliary bed-supporting frame B² is adapted to fold into parallel relation with the housing-section B¹ and to be locked thereto in the manner shown in Fig. 2, after

which the housing-section B¹ may be swung to the vertical position shown in Fig. 12 parallel with the stationary section B to which the section B¹ is releasably locked. As will be understood from Figs. 1-3, 7, 10, and 12, the member B² is equipped near its outer rail (assuming the structure to be in open condition), with a pair of bell-crank locking pawls 46, whose short arms are equipped with nose-portions 47 affording locking shoulders adapted to engage locking-plates or sockets 48 with which the rear portions of the end-members of the box B¹ are provided at their upper edges. With the long arms of the locking pawls 46 is connected a strap 49 adapted to effect release of the locking pawls. The strap 49 extends across the back side of the member B² in the manner indicated in Figs. 2 and 7, so that the strap can be readily grasped when it is desired to release the member B² from the member B¹. The pawls 46 are automatically thrown to the locking position by springs 50 (see Fig. 3). The lower rear corner of the frame B² is equipped with spring-catches 51 (Fig. 1) which are adapted to engage stationary catches 52 carried by the upper portion of the stationary housing-section B (Fig. 12).

When the structure is in the folded condition shown in Fig. 12, it may be converted to bed-form by lifting the front edge of the table-top slightly and shoving the table-top rearwardly, and then turning the table-top to the standing position shown in Fig. 1. The bed-structure may then be unfolded by swinging the housing-section B¹ downwardly from the position shown in Fig. 12 to the position shown in Fig. 2, the spring-catches 51 releasing, when force is applied. Through the medium of the strap 49, the auxiliary bed-supporting frame B² is then released from the housing-section B¹, and swung to the position shown in Fig. 8, and finally to the position shown in Fig. 1, after which the foot-section 28 is released from the intermediate section 27 and extended in the manner shown in Fig. 1. The arms 43 may be released from the locking studs 45 by manipulating the legs 40. The folding-bed frame is equipped with the usual flexible bottom, or wire fabric, 53. The head-section 26 is connected by spring-coils 54 to standards 55 which rise from the rear corners of the box B¹. The upper ends of the standards 55 are connected, by spring-coils, 56, with clips 57 which are secured to the lower portion of the stationary rear panel B. The springs 54 aid in the operation of lifting the head-section 26 of the bed out of the box B¹ in the unfolding operation; and the springs 56 aid in the operation of turning the swinging housing-section B¹ to a vertical position.

The operation of converting the structure

from bed-form to table-form will be understood without further description.

The bed-section 27 is equipped with gravity locking-pawl 57 (Figs. 1 and 8), which drop into locking engagement with the locking arms 43 when the section 27 is raised to a vertical position, as shown in Fig. 8.

The foregoing detailed description has been given for clearness of understanding only, and no unnecessary limitation should be understood therefrom, but the appended 10 claims should be construed as broadly as permissible, in view of the prior art.

What I regard as new and desire to secure 15 by Letters Patent is—

1. The combination with a table having a movable top, of a bed-housing disposed beneath said top and having a downwardly swinging section, and a folding bed carried 20 by said swinging section and comprising a plurality of foldably related bed-sections.

2. The combination with a table having a movable top, of a bed-housing disposed beneath said top and having a swinging section 25 connected at its lower portion to the ends of the table frame, and a folding bed carried by said swinging section and comprising a plurality of foldably related bed-sections.

3. The combination with a table having a movable top, of a bed-housing disposed beneath said top and having a swinging section connected at its lower portion to the ends of the table frame, and a folding bed 35 carried by said swinging section and comprising a plurality of main sections and spacing sections uniting them, said sections being united by pivots extending longitudinally with relation to the table.

4. The combination with a table having a movable top, of a bed-housing disposed beneath said top, comprising a fixed vertical section and a downwardly swinging section, and a folding bed carried by said swinging 45 section and comprising a plurality of foldably related bed-sections.

5. The combination with a table, of a bed-housing disposed beneath the table-top, comprising a vertical fixed rear panel, and 50 a downwardly swinging box-form housing-section whose bottom affords a front panel, and a folding bed carried by said swinging section and comprising a plurality of foldably related bed-sections.

55 6. In a structure of the character set forth, the combination with a frame, of a housing section pivotally connected therewith and adapted to swing from a horizontal position to a vertical position, an auxiliary bed-supporting frame foldably connected with said housing-section, and a folding-bed mounted on said housing-section and said auxiliary frame and comprising a plurality of foldably related bed-sections.

7. In a structure of the character set forth, the combination with a frame, of a box-form housing-section pivotally connected with said frame and adapted to swing from a horizontal position to a standing 70 position, an auxiliary bed-supporting frame foldably connected with said housing-section, a folding bed comprising a head-section movably mounted on said housing-section, a spacing section pivotally mounted 75 on said auxiliary frame and pivotally connected with said head-section, and a section pivotally connected with said spacing section and linked to said auxiliary supporting frame, and legs connected with said auxiliary supporting frame.

8. In a structure of the character set forth, the combination with a frame, of a swinging box-form housing-section adapted 80 to be turned from a horizontal to a standing position, an auxiliary bed-supporting frame linked to said housing-section and adapted to be folded into parallel relation with the housing-section, and a folding bed comprising 85 a plurality of foldably related sections mounted on said housing-section and said auxiliary supporting frame.

9. In a structure of the character set forth, the combination with a frame, of a swinging housing-section adapted to be turned from a horizontal position to a standing position, an auxiliary bed-supporting frame foldably related to said housing-section, means for locking said auxiliary 95 frame to said housing-section in a folded position, and a folding bed comprising a plurality of foldably related bed-sections mounted on said housing-section and auxiliary bed-supporting frame.

10. In a structure of the character set forth, the combination with a frame, of a swinging housing-section, an auxiliary bed-supporting frame foldably related thereto, means for locking said auxiliary bed-supporting frame to said housing-section when 100 said parts are in folded relation, a folding bed comprising a plurality of foldably related bed-sections mounted on said housing-section and auxiliary frame, and means for 110 releasably securing said housing-section in the standing position.

11. In a structure of the character set forth, the combination with a frame, of a housing-section connected therewith adapted 115 to swing from a horizontal to a standing position, a spring connecting said housing-section and said frame, said spring adapted to aid in turning the housing-section to the standing position, and a folding bed connected with said housing-section and comprising a plurality of foldably related bed-sections.

12. In a structure of the character set forth, the combination with a frame, of a 120

housing-section connected therewith adapted to swing from a horizontal to a standing position, a spring connecting said housing-section and said frame, said spring 5 adapted to aid in turning the housing-section to the standing position, an auxiliary bed-supporting frame foldably related to said housing-section, and a folding bed comprising a plurality of foldably related bed-sections mounted on said housing-section and auxiliary frame.

13. In a structure of the character set forth, the combination with a frame, of a swinging housing-section, an auxiliary bed-supporting frame foldably related thereto, legs connected with said auxiliary frame, and a folding bed comprising three main bed-sections and two spacing sections, the inner main section being linked to said housing section, the inner spacing section being pivotally connected with said auxiliary frame, and the intermediate main section being linked to said auxiliary frame, legs connected with the outer main section and linked to the outer spacing section, and means actuated by the intermediate main section and serving to actuate said first-named legs.

14. In a structure of the character set

forth, the combination with a frame, of a stationary vertical housing-section affording a rear panel, a swinging housing-section whose bottom affords a front panel, a folding bed comprising a plurality of foldably related bed-sections adapted to be carried by the swinging housing-section in the folding operation, and means for locking the swinging housing-section in symmetrical relation with respect to the stationary housing-section.

15. In a structure of the character set forth, the combination with a table provided with a movable top, of a vertical panel connecting the end-standards of the table in front of the rear edges of the end-standards, a housing-section connected with the end-standards of the table and adapted to swing from a horizontal position to a standing position and afford a panel between the end-standards and disposed in the rear of the front edges of the end-standards, and a folding bed carried by said housing-section and comprising a plurality of foldably related bed-sections.

PETER E. KROEHLER.

In presence of—
O. C. AVISUS,
D. C. THORSEN.
